UNITED STATES PATENT OFFICE.

NORA PARKER, OF OXFORD, MICHIGAN.

CORSET-STAY.

SPECIFICATION forming part of Letters Patent No. 752,297, dated February 16, 1904.

Application filed March 6, 1903. Serial No. 146,489. (No model.)

To all whom it may concern:

Be it known that I, NORA PARKER, a citizen of the United States of America, residing at Oxford, in the county of Oakland and State of Michigan, have invented certain new and useful Improvements in Corset-Stays, of which the following is a specification, reference being had therein to the accompanying drawings.

This invention relates to new and useful improvements in corsets, and relates more particularly to the steels or stays therefor, and has for its object to make a flexible stay which will lengthen or shorten to accommodate itself to the various bending movements of the body, a further object being to make a stay which may be securely fastened at its ends to the fabric to prevent the ends from wearing or working through the fabric, and at the same time provide means whereby the stay may have a limited movement upon itself to accommodate itself to the wearer.

To this end the invention consists in the novel construction, arrangement, and combination of parts, all as more fully hereinafter described, and shown in the accompanying drawings, in which—

Figure 1 is a front elevation of a stay embodying my invention; Fig. 2, a rear elevation thereof; Fig. 3, an edge elevation illustrating the operation of the stay; Fig. 4, an elevation illustrating my invention as applied to the front of a corset; Fig. 5, a section through a modified construction; Fig. 6, a section showing one method of fastening the clip to the stay, and Fig. 7 a section showing another method.

As shown in the drawings, A is the steel or stay, composed of two members *a* *b*, having a sliding or telescopic engagement with each

other. B represents clips secured to one stay member by uniting or otherwise and provided with inturned ends *c*, lapping the opposite side of the stay and forming guides for the other stay member to slide in, so that said members are free to slide upon each other to accommodate themselves to the various bending movements of the body of the wearer. The clips are preferably secured in place by punching a portion 56 of the clip right through an aperture in the

stay and riveting the bur on the other side; as shown in Fig. 6, or by separate eyelets, as shown in Fig. 7, and, if desired, they may be formed integral with the stay, the smooth side of the stay being preferably placed next to the body.

In Fig. 5 I have shown a modified construction in which one of the members is provided with a slot *d*, and the clip completely encircles both members of the stay, a rivet *e* passing through said slot, as shown. C represents apertures in the opposite ends of the stay for securely fastening them in place by sewing or otherwise.

My invention is designed and applicable to 65 wearing-apparel in general, and while I have described my invention as applied to a corset it is obvious that it may be used for dress-stays as well.

In applying my invention to the construction of supports for corsets or garments generally it may be manufactured and sold as a new article of manufacture, and when I say steel I mean any article in the nature of a corset-steel.

To those at all familiar with the annoyance of the ordinary corset-steel the advantages of my construction will be readily apparent.

Having thus fully described my invention, what I claim is—

1. A stay for wearing-apparel comprising a plurality of members having telescopic engagement with each other, means on one of said members having inturned ends for embracing the other member, and means passed through said means and its member for securing said means and member together, the securing means being confined between said member and the said means with inturned ends.

2. A stay for wearing-apparel comprising a plurality of members having telescopic engagement with each other, means on one of said members having inturned ends for embracing the other member and means integral with said means passed through its member and upset upon the opposite side thereof.

3. A stay for wearing-apparel comprising a plurality of members having telescopic engagement with each other, means on one of

said members having inturned ends for embracing the other member, and means integral with said means passed through its member and upset upon the opposite side thereof, the upset portion being between said member and the guiding means.

4. A stay for wearing-apparel comprising a plurality of members having telescopic engagement with each other and a clip having inturned ends embracing the edges of one member and adapted to receive the other member, said clip having a portion punched out

and passed through an aperture in its member and riveted upon the side of said member through which the punched-out portion passes, 15 opposite that against which said clip bears, substantially as and for the purpose specified.

In testimony whereof I affix my signature in presence of two witnesses.

NORA PARKER.
